UNITED STATES PATENT OFFICE

BENJAMIN WOLHAUPTER, OF NEW YORK, N. Y., ASSIGNOR TO THE RAIL JOINT COMPANY,
OF NEW YORK, N. Y., A CORPORATION OF NEW YORK.

RAIL-JOINT.

No. 908,530.

Specification of Letters Patent.

Patented Jan. 5, 1909.

Application filed October 29, 1907. Serial No. 399,713.

To all whom it may concern:

Be it known that I, BENJAMIN WOLHAUPTER, a citizen of the United States, residing at New York city, in the county of New York and State of New York, have invented certain new and useful Improvements in Rail-Joints, of which the following is a specification.

This invention relates to the subject of rail joints particularly of the type embodying a rail supporting base or base plate.

To this end the invention has in view the provision of a simple and practical construction of rail joint in which the parts are so related and combined as to effectually secure the same against relative movement, while at the same time maintaining a firm bearing contact between the various members constituting the joint.

A further object in this connection is to provide a construction wherein the base plate is securely clamped beneath the rails in such a manner that there is no tendency of the central portion of said plate to spring, or be forced, away from a firm bearing contact beneath the rails.

A further object of the invention is to provide improved clamping means for the base plate of the joint, which clamping means are of a resilient character so as to not only secure the functions above indicated, but also to provide a spring action which is of practical benefit in maintaining the parts firmly clamped together. Also, the improved clamping means are adjustable to compensate for wear or loosening by vibration.

A further general object of the invention is to provide a construction of joint possessing special utility as an insulated rail joint for use in connection with track circuits, and to that end the improvements referred to are intended to effectually secure the insulation in place and minimize the relative movement of the parts to such an extent as to minimize the wear on the insulation.

With these and other objects in view, which will readily appear to those familiar with the art, the invention consists in the novel construction, combination and arrangement of parts hereinafter more fully described, illustrated and claimed.

In the suggested embodiments of the invention shown in the drawings, the essential

features of the invention are exemplified, and in these drawings:

Figure 1 is a sectional perspective view of an insulated rail joint embodying the improvements claimed herein. Fig. 2 is a cross sectional view of the improved construction of joint illustrating a modification of the clamping engagement between the base clamp and base plate. Fig. 3 is a detail sectional view through a portion of the base plate and the adjacent clamping portion of the clamp, the plane of section being indicated by the line 3—3 on Fig. 2. Fig. 4 is a detail in perspective of the bottom insulating sheet such as used in the relation shown in Figs. 1 and 2. Fig. 5 is a perspective view of a two-part or composite bottom filler that may be utilized in a modification of the joint. Fig. 6 is a longitudinal sectional view of a modified form of joint which embodies the two-part bottom filler shown in Fig. 5.

Like references designate corresponding parts in the several figures of the drawings.

The improved joint contemplated by the present invention includes in its organization the usual service rails 1 and 2, the opposite side angle bars 3—3, and a rail supporting base plate 4. The base plate 4 subserves the usual functions of a metallic rail supporting base or base plate, and extends the full length of the joint as well as being of a width coextensive with the width of the rail base flanges. The side angle bars 3 are arranged in the fishing spaces and are preferably of the conventional design so as to have the usual bearing beneath the rail heads and over the rail flanges, but in addition to these necessary features of the angle bars, the present invention contemplates designing said bars so as to provide the same at their lower edges with the horizontal off-standing foot flanges 5 projecting beyond the edges of the rail flanges and disposed above the plane of the bottom faces of the rails. These off-standing foot flanges 5 are preferably formed integrally with the bottom bearing feet 6 of the angle bars, and are utilized as the supporting members for the upstanding threaded bolt ends 7 of the clamp yokes 8 which constitute base clamps for forcing the base plate upward under the rail bottom.

In carrying out the invention, a plurality

of the base clamps are usually employed, there being one or more of such clamps arranged at each side of the joint between the meeting ends of the rails, but irrespective of the number of clamps employed and the particular disposition thereof, the construction and action of each clamp is the same.

While clamps of different specific construction may be used for the purposes of the present invention, a simple and practical design of clamp is shown in the drawings, in which drawings each clamp is illustrated as preferably consisting of the clamp yokes 8 in the form of U bolts having the opposite 10 terminal upstanding bolt flanges 7 referred to and the intermediate or connecting bar 9 which lies transversely beneath the base plate 4 so that the opposite bolt ends 7 will connect with the supporting foot flanges 5 of 15 the opposite angle bars. The said bolt ends 7 of each clamp yoke extend through bolt openings 10 provided therefor in the supporting flanges 5, and the upper extremities of the bolt ends above said flanges receive 20 thereon the clamp nuts 11 which provide for adjustably securing the clamp yoke to the opposite angle bars and against the base 25 plate 4.

A distinctive and characterizing feature of the present invention resides in providing a clearance between the side edge portions of the base plate and each clamp yoke so that the bolt ends and the adjacent cleared portions of the connecting bar 9 will be permitted to have a vertical spring action, and thereby maintain the parts held by the clamps, under constant spring pressure. Furthermore, the detail referred to causes the central portion 12 of each yoke to act as an intermediate clamping portion which is held 30 under direct clamping pressure against the central part of the base plate between the side edges of the latter. The effect of this is to effectually force the base plate up under 35 the rails through the tightening of the bolts 11, and also positively obviating any tendency of the central portion of the base plate moving away from a firm bearing contact 40 beneath the rails.

In the form of the invention shown in Fig. 1, the direct bearing or fulcrum engagement between each clamp yoke and the central portion of the base plate is secured and maintained by providing the connecting bar 45 9 of the yoke with a slight upward bow or arch. The same result is accomplished by practically a reverse of this construction, viz: to leave the connecting bar 9 of the yoke substantially straight and forming the base plate where each yoke is placed, with a transverse retaining groove 13 having a raised central portion and deepened end portions 14, the latter providing the necessary clearance for the end portions of the yoke

, provide for the spring action and central bearing referred to. (See Fig. 2).

The rail joint proper is completed by a series of the usual joint bolts 15 passed through the regulation bolt holes in the rail webs and the side angle bars.

The joint construction described possesses special utility when employed with insulating means to provide an insulated rail joint. A joint of this character is produced by fitting the joint bolts with any suitable bolt 75 insulation 16, and employing the side insulating sheets 17 between the angle bars and rail sides, and the bottom insulating sheet 18 between the rail bottoms and the base plate 4. With this arrangement it is preferable to have the bottom insulating sheet 18 wider than the rail bases and base plates and to form in the projecting side edges of said bottom insulating sheet the keeper notches 19 receiving the bolt ends 7 of the 85 yokes which therefore act as guards to prevent relative displacement or movement of the said insulating sheet 18. Also, the said bolt ends 7 are brought as close as practicable to the rail flanges and base plate so 90 as to prevent lateral shifting of the latter.

Instead of employing a continuous all-insulating sheet 18, there may be employed a two-part or composite bottom filler such as shown in Figs. 5 and 6 of the drawings. 95 This bottom filler consists of two parts, viz: an insulating base section 20 and a metallic bearing plate section 21, the latter being arranged beneath the receiving rail in order to give a metal support thereto, as may be 100 best seen in Fig. 6 of the drawings.

To complete the insulation of the joint referred to, there may be used the conventional insulating end post 22.

Other adaptations and modifications of the invention will be readily apparent without further description, and it will be understood that various changes in the form, proportion and minor details of construction may be resorted to without departing from 105 the principle or sacrificing any of the advantages of the invention.

I claim:

1. In a rail joint, the rails, side angle bars, a base-plate separate from the angle bars and underlying the rail bases, a transversely arranged spring-clamp supported from the lower edge portions of the opposite angle bars and having a spring-clamping engagement with the central part of the 115 base-plate, and also having a clearance from the edge portions of said plate.
2. In a rail joint, the rails, side angle bars bolted to the rails, a base-plate separate from the angle bars and underlying the rail bases, and a transversely arranged U-shaped yoke having bolt ends adjustably connected with the lower edge portions of the angle

bars, and an intermediate clamping portion held upward by spring pressure against an intermediate part of the base-plate.

3. In a rail joint, the rails, side joint bars, 5 a base plate, insulation for the joint parts including a bottom insulating sheet arranged between the base plate and the rail bottom, and a transversely arranged spring U clamp yoke extending beneath the base plate and 10 having bolt ends connected with the joint bars, said bolt ends being also interlocked with the said insulating sheet.

4. In a rail joint, the rails, side angle bars, 15 a base plate, a two-part filler comprising an insulating base section arranged between the base plate and one rail end, and a metallic bearing plate section interposed be-

tween the base plate and the other rail end, and transversely arranged resilient U-shaped clamping bolts embracing the base plate and 20 adjustably bolted to the angle bars.

5. In a rail joint, the rails, side angle bars bolted to the rails, a base plate, and a transversely arranged base clamp having resilient end portions connected with the angle bars 25 below the line of joint bolts, and a clamping portion held upward by spring pressure against the central part of the base plate.

In testimony whereof I hereunto affix my signature in the presence of two witnesses. 30

BENJAMIN WOLHAUPTER.
